UNITED STATES PATENT OFFICE.

RUDOLF LOEB, OF CAMDEN, NEW JERSEY.

PROCESS OF EMBROIDERING.

1,194,521.

Specification of Letters Patent. Patented Aug. 15, 1916.

Application filed October 2, 1912. Serial No. 723,572.

To all whom it may concern:

Be it known that I, RUDOLF LOEB, a citizen of the United States, and a resident of Camden, Camden county, New Jersey, have 5 invented an Improved Process of Embroidering, of which the following is a specification.

My invention relates to surface fabric ornamentation known as embroidery, more 10 particularly to embroidery mechanically applied to sections of fabric for use as ornamental covers, doilies, center pieces and the like, employed on tables, &c., and the object of my invention is to produce an improved 15 character of eyelet embroidery with stitched edge.

These and other features of my invention are more fully described hereinafter, reference being had to the accompanying 20 drawings forming part thereof, in which:

Figure 1, is a view illustrating a piece of fabric and a holder for the same; such fabric being shown in course of ornamentation in accordance with my invention; Fig. 2, is 25 a perspective view illustrating the manner of effecting the inclosure of the edges of openings formed in such fabric; Fig. 3, is an enlarged plan view of an eyelet or aperture with its edges bound in accordance with my 30 invention; Fig. 4, is a sectional view of the fabric before the eyelet is bound; Fig. 5, is a sectional view on the line $a-a$, Fig. 3, and Fig. 6, is a view of a modified arrangement.

The object of my invention is to produce 35 eyelet or apertured embroideries. To this end a piece of fabric 1 is prepared by slitting the same as at 2; such fabric being then stretched in an ordinary tambour frame, such as 3, and then by means of a sewing 40 machine employing an oscillating needle, indicated at 4, with the usual shuttle, I form stitches 5 on both edges of the slits, as shown in the drawings. In forming these stitches, the oscillating needle is employed by the 45 operator to impart slight movement to the said edge, which, of course, owing to the flexing or giving of the goods, will be greater adjacent the middle of the slot so that as a final result, a hole or aperture is 50 formed with its edge bound with stitches formed by the needle and shuttle threads,

which hole may be oval, or elongated in the manner indicated in the drawings. During this operation the needle in forming the stitches 5 catches up a portion of the fabric, 55 as indicated at 6, in Fig. 2, and tucks the same under the edge of the aperture; being completely inclosed by the stitches formed by the needle and shuttle threads. Such caught portion of the fabric serves to stuff 60 the stitched edges of the apertures and acts further as a stiffener for the same.

In the form of embroidery shown in Figs. 1 and 3, the stitches are laid substantially parallel to each other, as clearly indicated 65 by the drawings, while in the form shown in Fig. 6, the fabric has been moved while the stitching is effected so that the stitches are radially disposed.

I claim:

1. The process of embroidering fabrics, which consists in stretching the fabric, slitting the same, and applying stitches to the edges of the slit portion, the application of said stitches simultaneously pulling the edge 75 of the fabric whereby the slit may be widened and the edge thereof caught up, turned under and inclosed by the stitches.

2. The process of embroidering fabrics, which consists in stretching the fabric, slitting the same, and applying paralleling 80 stitches to the edges of the slit portion, the application of said stitches simultaneously pulling the edge of the fabric whereby the slit may be widened and the edge thereof 85 caught up, turned under and inclosed by the stitches.

3. In the formation of eyelet embroidery, the process which consists in stretching the fabric and mounting it in a carrier, slitting 90 said fabric, and applying stitches to the fabric at the margin of the slits, the application of said stitches simultaneously pulling and folding the fabric adjacent the slits whereby such portion may be caught under 95 said stitches to stuff the stitched marginal edge or border of said eyelet.

4. In the formation of eyelet embroidery, the process which consists in stretching the fabric, slitting the same by cutting the 100 threads thereof, and applying a plurality of paralleling stitches to the fabric at the slit

portion thereof, the application of said stitches simultaneously pulling and folding the fabric adjacent the slits whereby such portion may be caught under said stitches to stuff the stitched marginal edge or border of said eyelet.

In testimony whereof, I have signed my

name to this specification, in the presence of two subscribing witnesses.

RUDOLF LOEB.

Witnesses:

WILDA B. BESSER,
JAMES W. REANEY.
